CLAIM

The ornamental design for a patient transport device, as shown and described.

DESCRIPTION

FIG. 1 is a top perspective view of a patient transport device showing our new design in the prone position thereof;

FIG. 2 is a side perspective view thereof;

FIG. 3 is an end perspective view thereof;

FIG. 4 is end perspective view thereof;

FIG. 5 is an end perspective view thereof in one of several adjustable seat positions;

FIG. 6 is a top perspective view of the seat position;

FIG. 7 is a side elevational view of the seat position and the opposite unillustrated side being substantially a mirror image thereof;

FIG. 8 is a side elevational view of another adjusted seat position;

FIG. 9 is a top plan view of the patient support in the prone position;

FIG. 10 is a bottom plan view of the prone position;

FIG. 11 is a side elevational view of the prone position and the opposite unillustrated side being substantially a mirror image; and,

FIG. 12 is an end elevational view and the opposite unillustrated side being a mirror image.
